HERMAN C. NIELSEN, OF MEMPHIS, TENNESSEE

BLOCK FOR FLOORING

Application filed March 14, 1929. Serial No. 347,044.

The present invention relates to blocks and block flooring, the blocks being made up in the manner described below in such a way as to be readily assembled at the point of use 5 to form a floor which will combine durability, beauty and any desired color effects.

In Figure 1 I have shown a top plan view of a modification in which the top of the edge is square. Figure 2 is a similar view 10 with the top of the edge beveled off on all four sides of the block to give a V shaped shallow trough around the edge of each square, after laying the floor.

Figure 3 is a top plan view and Figure 4 15 is a vertical section on the line 4—4 of Figure 1, of a portion of completed floor using the blocks with the square top edges. Figure 5 is a side view of such a block showing large dowel pins. Figure 6 is a side view 20 of a similar block having smaller dowel pins.

Figure 7 is a top plan view and Figure 8 is a vertical section of a portion of a floor in which the blocks with beveled top edges 25 are employed.

The lumber from which the blocks are made is of any desired variety, and this lumber is first impregnated with a water-proofing material, such for example as that disclosed in my copending application of even 30 date herewith. This water-proofing material should be such as to give a substantially complete water-proofing of the block and any desired coloring of the wood, without leaving an excess of oil to bleed out during 35 handling or during changes in temperature to which the product would ordinarily become subjected. The boards may be of the cross section shown in Figure 8 if desired.

For assembling the boards together I may 40 use large dowel pins 11 as shown in Figure 5 or I may use smaller dowel pins as shown at 12 in Figure 6. The larger dowel pins are preferred, and these dowel pins are preferably first soaked in a glue solution, for 45 which purpose casein glue has been found to be very satisfactory. Heretofore in making blocks of the general character here referred to, it has been the practice to groove all the way around a block or on three sides 50 of the block, and to introduce separate

tongues or splines which are nailed into the grooves on two adjacent sides. I have shown that when using a water-proofed wood as in the present invention it is considerably more advisable to make the tongues integral 55 with the board, not only on the sides but also on the end of the block. The boards used are preferably tongue and grooved boards. The tongues are shown on the edge of the block at 13 and on the end of the block at 14 and I call attention to the fact that the corner of the tongue is preferably cut off as shown at 15 in Figures 1 and 2. The joints 16 between the several boards in a particular block are preferably filled at 60 the time of making the block with a suitable water-proof adhesive such as casein glue.

It will be noted that in Figure 4 and Figure 5 the dowel pins are shown as being of a diameter somewhat greater than the width 70 of the groove 17 and accordingly greater than the thickness of the tongues 13. These dowels are preferably placed in holes which are very slightly above the vertical center of the board and thereby the dowel holds the surface of 75 the board together much better than would be the case if the dowels were lower down.

It will be noted that the dowel pins project across the tongues so that they extend across the grain of the tongues and prevent 80 slivering of these parts. Also they form a secure positioning means for the next block.

I may alternate dark and light colors, or wood of natural color and dyed wood, checkerboard fashion in the floor to be made, or 85 I may arrange the different colored blocks in such a way as to produce other effects, such as borders and the like.

The blocks as made at the factory are preferably finished, that is to say planed or sandpapered and varnished, preferably with a transparent varnish so that an entire floor can be laid without subsequently varnishing the floor.

As pointed out in my copending application above referred to, lacquer varnish will adhere to the water-proofed wood without cracking or peeling or separating from the wood.

There is a special function in the V shaped 100

shallow troughs 18, produced by the beveled edges of the blocks, in connection with a varnished flooring, the elements of which have been surface coated at the factory, in that any slight differences in thickness of the different blocks will not be apparent in the finished floor. In some cases it may be advisable to fill this V shaped trough 18 with a suitable plastic composition, which may be of a different color from any of the blocks constituting the floor or in case the floor is made of uncolored wood, the composition may be of the same color as the wood or a different color if desired.

15 In the above description I have referred particularly to the use of these blocks in making floors. It will be understood that the blocks are also applicable with similar advantages for other interior trimming, as for 20 example wainscoting, ceilings, paneling and the like.

It is rather surprising that casein glue or similar glue will adhere well to an oiled wood, both in connection with the dowel pins and 25 in connection with gluing the edges of the boards together in the block. In this connection I call attention to the fact that the wood is impregnated with such an amount of oil only as will constitute a film on the surface of each cell wall, without completely filling the cells.

I claim:—

1. A floor block having a tongue formed on one side edge, and a groove on the other 35 side edge, said block consisting of a plurality of boards arranged side by side and having dowel pins extending transversely therethrough and into the said tongue whereby to reinforce the latter.

40 2. A floor block consisting of a plurality of tongued and grooved boards arranged side by side and having dowel pins extending transversely therethrough and into the tongue at the edge of the block whereby to 45 reinforce the tongue, said dowel pins being of greater diameter than the width of the groove and extending flush with the grooved outer edge of the block whereby to interlock with the tongue of the adjacent block.

50 In testimony whereof I affix my signature.

HERMAN C. NIELSEN.
